PACKAGE WRAPPING MACHINE

Walter Rubel, Cincinnati, Ohio

Application December 27, 1933, Serial No. 704,105

4 Claims. (Cl. 271—2.1)

An object of my invention is to produce a tightly wrapped package when this is desirable in preference to a loosely wrapped package as now produced by the existing type of automatic 5 wrapping machine in universal use, by which a roll of paper or "cellophane" is used to wrap packages such as bread and the like.

A further object of my invention is to control 10 the idler roller which functions by rotatively pressing against the perpendicular sheets of wrapping material used in making loosely wrapped packages, by rotating the idler roller in the opposite direction to the direction of the wrapping material and thereby cause a certain 15 amount of retardation or resistance to the wrapping material to cause it to make a tightly wrapped package. This function being carried out without changing any of the parts of the existing machine.

20 The mechanism described herein to accomplish either a loose or tight wrapping of packages is so constructed that it does not interfere with any of the parts of the existing construction of an automatic wrapping machine excepting 25 in the control of the idler roller by means of my mechanism and the use of a horizontal sprocket chain positioned on the top side of the machine. This chain although used to drive other parts of the machine is adapted for engagement with a sprocket wheel of my mechanism 30 for driving the same.

In the accompanying drawings:—

Figure 1 is a plan view of the mechanism,

35 Figure 2 is a side elevation of the mechanism showing the position of it with relation to the existing machine,

Figure 2a is a partial top plan view of the guide roller,

40 Figure 3 is a modification of the invention, and

Figure 4 is a further modification of the invention.

In Fig. 1 the shaft 1 rotates in its housing 2, a collar 2' is on the end of the shaft with a set 45 screw 3 for securing the collar to the shaft so as to prevent displacement of a combination sprocket wheel and spur gear wheel 4, loosely mounted on the shaft between the collar 2' and the end of the housing 2, the housing being 50 mounted on a base 31 which is bolted down on an extension bracket 32 of the original machine. An aperture 5 is bored in the shaft and a spring 55 button 6 is mounted on the hub of the combination sprocket and spur gear wheel 4, with the end of the button 7 adapted to engage the aperture 5, the purpose of which will be hereinafter described. The sprocket wheel 4' engages with a horizontal driving sprocket chain 3' of the machine for driving other parts of the machine 60 and which I utilize for driving my mechanism

without interference with these other parts. At the other end of the shaft 1 is mounted a small sprocket wheel 8 and a large sprocket wheel 9, integral with one another, and pinned fast to the shaft 1 with a taper pin 10 and adjacent to the 5 other end of housing 2.

A second housing 11 is mounted on the plate 31, mounting a shaft 12; set into one end of the shaft 12 is a spline 13 upon which is slidably mounted the spur gear wheel 14 its teeth 15 meshing with 10 the teeth of spur gear wheel 4" mounted on shaft 1, the hub 16 of the spur gear wheel 14 has an annular recess 17 to receive therein the spanner device 18 which controls the slideable operation, the spanner device 18 with its handle 19 15 is swiveled by screw 20 for moving the teeth 15 and 4" in and out of mesh. In order to prevent displacement of gear 14 from its shaft a collar 21 is pinned thereon with a taper pin 22, and adjacent the housing is a collar 23 also 20 pinned to the shaft 12 with a taper pin 24. Mounted on the other end of the shaft 12 is a sprocket wheel 25 pinned thereon by taper pin 26, a sprocket chain 26' connecting sprockets 8 and 25.

The shaft 1 rotates sprocket gear wheel 9 connected as shown in Fig. 2 with sprocket wheel 27 by sprocket chain 28. Figure 2a shows a clamp bracket or housing 29 on which the roller 30 is rotatably mounted, the collar 29' and the hub of 30 sprocket wheel 27 prevents displacement of the roller in the mounting. The other end of the roller 30 is mounted rotatably by a V shaped screw 31 as originally mounted in the machine in which roller 30 was the idler roller.

In Fig. 1 the spur gears 4" and 15 are in mesh, while the end of the button 7 is withdrawn from the aperture 5 bored in shaft 1. The arrow in Figure 1 points to the right which is the direction in which the sprocket chain 3' travels in the 40 original machine and with which the sprocket gear wheel 4' is adapted to mesh. When the machine is started the sprocket wheel 4' is rotated to the right and the spur gear wheel 4" also revolves to the right and is meshed with spur gear 14 so that the shaft 12 is thereby rotated to the left and in which direction the sprocket wheel 25 turns. The sprocket chain 26', in turn, drives sprocket wheel 8 and the shaft 1 to the left thereby turning the large sprocket wheel 9 to 50 the left and the chain 28 drives sprocket wheel 27 which in turn drives the roller 30 to the left for loose wrapping of packages. This is brought about by reason of the button 6 being turned so that its end 7 is withdrawn from the aperture 5 bored into shaft 1 and the intermeshing of the spur gear wheels 4" and 14.

For tight wrapping of packages the spur gear 14 is disengaged by the spanner device 18 from spur gear 4" and the button 6 is turned to allow its 55

end 7 to engage aperture 5 in shaft 1 whereby a disengagement is brought about although shaft 12 will rotate as will the sprocket wheel 25 connected by chain 26 with sprocket wheel 8. This, however, does not interfere in the least with the mechanism revolving to the right, thus the sprocket wheel 4' is in engagement with the sprocket chain 3' running horizontally in the original machine, but as above stated shaft 1 when connected with the end of the button pin 7 becomes an entirety revolving all its attached mechanisms to the right. The roller 30 rotates therefore to the right causing by such action a retardation or resistance against the wrapping material as it is fed forward for wrapping purposes in the original machine and thus causes the production of a tightly wrapped package. With the addition of my mechanism to the original machine a loose or tight package wrapping is effected.

The mechanism described above may be modified as shown in Figures 3 and 4.

Figure 3 discloses a mechanism which will turn shaft 33 either to the right or to the left by means of slideable bevel gears 39. A housing 34 is attached to bracket 31 shown in Fig. 2 connecting therewith and supported thereby are arms 35 with housings 36 at their ends for housing shaft 33. Collars 37 mounted on the shaft to prevent displacement of the housings, splines 38 set into the shaft, slideably mounted bevel gears 39 mounted on shaft 33, an elongated collar 40 pinned by taper pin 41 to shaft 33 to separate the bevel gears for proper engagement with central bevel gear 42 mounted on a shaft 43 in the housing 34. Recesses 44 in bevel gears 39 to engage spanner levers 44' at their ends 45, the levers being pivoted at 46 on the arms 35, for the purpose of throwing each gear in or out of mesh with central bevel gear 42.

Secured to the outer end of the shaft 43 is mounted a sprocket gear wheel 48 and pinned thereto with taper pin 49. Since this sprocket wheel engages with the horizontal sprocket chain of the machine proper and travels to the right at all times consequently the central bevel gear 42 always travels to the right. Therefore if shaft 33 is to travel to the right the upper gear 39 is disengaged from the central bevel gear while the lower bevel gear 39 is meshed with it. This will turn the lower bevel gear to the right and transmit this direction to lower bevel wheel 50 pinned to shaft 33 and supported by its housing 51 which is supported by arm 52 attached to housing 53 in which rotates the roller shaft 54 to which is pinned the roller 55 the end of which is supported by a V shaped screw in the V shape aperture 56. At the inner end of the roller is the bevel wheel 57 pinned to the shaft with taper pin 58.

To turn the shaft 33 to the left the spanner wrench lever moves the lower bevel gear 39 out of mesh from the central gear 42, (this is always done when the machine is stopped) the upper bevel gear 39 is then thrown into mesh with the central bevel gear 42 and as this central gear travels to the right it in turn will rotate the upper bevel gear 39 to the left and this in turn drives the shaft 33 to the left and the roller bevel gears and roller to the right, which movement is for tight wrapping of packages.

To turn the roller to the left, lower bevel gear 39 is thrown into mesh by its spanner wrench lever with central gear 42 and the upper gear is thrown out of mesh with the central gear, the

shaft 33 will then rotate to the right and the roller to the left for loose wrapping of packages.

In Figure 4 we deal with disk and friction wheels. The disk 59 is fastened to shaft 60 by pin 61 and rotates in the housing 62. At the end of the shaft 60 is the sprocket wheel 48 (see Fig. 3) arms 63 with housings 64 at each end thereof in which rotates shaft 65 with collars 66 at each of its ends, inside the housings set into the shaft 65 are splines 67 to slidably mount the friction wheels 68 on the shaft 65, recesses 68' are engaged with spanner wrench levers 69 which levers are pivoted on arms 63 by screws 70. The rotation to the right or left of the shaft 65 is effected as described above in Fig. 3. The shaft 65 is broken away at its lower end for the reason that the same construction for the extension of shaft 65 is as is shown in Fig. 3 at the end of the shaft 33. Repetition was thought unnecessary in this respect as it is amply shown in Fig. 3.

It is to be understood that the form of my invention, herewith shown and described can be modified by various changes in the shape, size and arrangement of parts without departing from the spirit of my invention, or the scope of the subjoined claims.

Having thus described my invention, I claim:

1. In a package wrapping machine, the combination of means for supporting a roll of wrapping material; with a guide roller having frictional slip contact with the wrapping material drawn from the roll of wrapping material, and reversible mechanism for rotating the guide roller about its axis in either a clockwise or counter-clockwise direction to tension the wrapping material by the frictional slip contact therewith.

2. In a package wrapping machine, the combination of means for supporting a roll of wrapping material; with a guide roller having frictional slip contact with the wrapping material drawn from the roll of wrapping material, reversible mechanism for rotating the guide roller about its axis to tension the wrapping material by the frictional slip contact therewith and a main driving means for actuating the reversible mechanism.

3. A package wrapping machine as claimed in claim 2, wherein the reversible mechanism includes a first and second shaft, means for driving the first shaft and the guide roller in the same direction, means for driving the first and second shafts in the same direction, disengageable means for driving the first shaft by the main driving means and disengageable means for reversing the rotation of the second shaft with respect to the driving means.

4. A package wrapping machine as claimed in claim 2, wherein the reversible mechanism includes a first and second shaft, a chain and sprocket mechanism for transmitting the drive from the first shaft to the guide roller, a second chain and sprocket mechanism for transmitting the drive from the second shaft to the first shaft, a combined sprocket and spur gear wheel disengageably mounted on the first shaft, and a spur gear wheel disengageably mounted on the second shaft, with respect to the spur gear wheel on the first shaft, said spur gearings operating to transmit a reverse drive from the combined sprocket and spur gear wheel to the second shaft.

WALTER RUBEL.
